UNITED STATES PATENT OFFICE.

WILLIAM M. BAGER, WERNER LEHMAN, AND FREDERICK CARL RUHLOFF, OF SOUTH MILWAUKEE, WISCONSIN.

DIPPER FOR EXCAVATING MACHINERY.

Application filed September 2, 1925, Serial No. 54,025. Renewed November 10, 1926.

This invention relates to dippers used on excavating machinery, and has particular reference to the construction of such dippers by casting them in two pieces; and has further particular reference to the construction, arrangement, and means of attachment of the teeth that are applied to the forward or cutting edge of the dipper front, and to the corresponding form and construction of said dipper front.

We are aware that a two-piece dipper is not new in the art; but heretofore the plane of division between the two parts has been taken parallel to the front, or digging face, of the dipper; whereas we have effected a great improvement by making the plane of division substantially parallel to the bottom, or door, of the dipper.

Departing from all former methods of construction, our invention divides the dipper in a novel way, in that we are combining in one unitary casting the entire upper part of the dipper, carrying the cutting lip and teeth and the principal attachment lugs; while the lower part virtually forms merely a receptacle and discharging means for the excavated material.

The digging resistance is applied directly at that portion of the upper part which contains the teeth, and the power is applied at the bail attachment, both of these being on the same casting, and the horizontal plane of junction being one in which no stress is transmitted from lip to bail. There are no excessive strains on the junction of the two members, as there would be on a two-piece dipper divided vertically as heretofore. Hence no great multiplicity of rivets or bolts is required to hold the two pieces together. Furthermore our few bolts have their lengths lying in the direction of the maximum component of the stress at the junction, and are therefore primarily in tension. The small amount of shear is entirely taken up by surrounding a few of the bolts by shear plugs, finished to a perfect fit. All our bolts are well protected, and are easily removable by the ordinary shovel crew.

The upper and lower pieces may be made of metals differing in composition and characteristics, suiting the composition of each to the work which it is required to do.

The two portions of the dipper join on a finished face, and the bolt holes are drilled to template, thus insuring perfect fit in replacements.

The combination, with the upper half of the dipper, of attachments for back-brace, bail, and teeth, has enabled us to make various other economies in cost, time and labor, which are not obtainable with a two-piece dipper divided, as heretofore, in a plane substantially parallel to the cutting front.

The upper casting of our dipper includes all the usual wearing parts, and if worn out will require less replacement than in the case of dippers with a vertical front casting. The shape of the dipper front and the location of the tooth points are such that we can expect greatly reduced wear of the bottom band compared to that of the old design dippers.

Our dipper-front construction is novel in the manner in which the two walls of which the front is composed are held apart by horizontal ribs or webs, and are joined together between the teeth to form a cutting edge. The front is therefore virtually a double trussed structure. Although in the accompanying drawings our dipper-front is shown as having the arch form which is approved for certain classes of excavating work, the invention is as easily applicable to the straight form of front which is desirable in such work as coal-stripping.

With our form of dipper-front, it is also possible to place a tooth considerably nearer to the corner of the dipper than is usual. This is especially desirable in rock work, and serves to reduce the wear upon the lip at the corners.

The two plates of the front, together with the horizontal webs which space them apart, form sockets providing a very rigid holding for the teeth. The joinings of the two plates at the lip hold the tooth effectively against

any sidewise motion. Our very rigidly trussed sockets therefore serve better than four-walled sockets which latter would be extremely difficult to cast for proper fit of the tooth. A four-walled socket would require either a careful machining of at least two of the walls, or else securing the tooth in place by bolts or similar means, which is troublesome; whereas, in the case of our socket, it is a simple matter to chip the edges of our webs so as to fit our teeth, and thus hold them in place by friction alone. Furthermore inasmuch as our sockets open into each other, it is much easier to free them of dirt than if they each formed a closed receptacle. This ease of cleaning is especially evident at the bottom, where, on two opposite sides, the socket is accessible from the outside.

20 At the base of each tooth-socket we provide a hole, for the insertion of a tool to drive the tooth out of the socket when it is desired to repoint or replace it.

As our sockets are all identically of the same standard form, any tooth may be used in any socket, since our invention contemplates making all teeth of the same form in that portion of their length which is inserted in the socket. It is, however, quite within the domain of our invention to provide teeth whose cutting portion may be any one of several different standard forms, the particular form used being dependent upon the character of the work to be done. The same teeth will also be applicable to different forms of excavator, such as shovel, dredge, etc.

Since our tooth is held frictionally, instead as heretofore by some such means as a bolt, it also becomes possible to advance the tooth with respect to the lip, by inserting a filler or spacer within the socket at the base of a tooth which has been shortened by wear.

The upper side portion of the dipper has a flare at the bail attachment, so that the bail does not project inwardly beyond the normal face of the dipper, thereby interfering with digging. This flare also permits a simplified bail lug connection, reducing the usual projection of the side lugs, which in rock work are subject to excessive abrasion.

The bail ends are bifurcated and are made exceptionally heavy, so that they may give longer service. As the wear is mostly on the front side of the bail ends and as our bail is reversible, this reversibility provides two wearing surfaces, thus increasing the life of the bail.

The lower half of the dipper combines in one unitary casting the connections for the door and the handle and an integral latch-keeper. This lower casting is made with inside dimensions at the bottom slightly larger than those at the top, this flare increasing the ease of dumping.

A latch-keeper made integral with the dipper, which construction is particularly desirable in rock work, eliminates one trouble which the separately cast and attached latch-keeper frequently causes by becoming loose. 70

The door is of the usual construction, provided with a wearing-plate at the center for rock work.

From the foregoing it is evident that we have provided a dipper applicable to various types of excavating machinery, that is novel, strong, durable, relatively light in weight, economical in cost, easily assembled or disassembled, and can be repaired with a minimum of delay; besides being equipped with a cutting tooth that is simple in construction, interchangeably to any socket, easily attached and easily removed for replacement or repointing, and rigidly held in its operative position. 85

Other objects and advantages of our invention will be evident to those skilled in the art, and therefore need not be herein more specifically set forth.

The invention consists in the novel parts and in the combinations and arrangements defined in the appended claims, and of which one embodiment is exemplified in the accompanying drawings, which are hereinafter particularly described and explained. 95

Throughout, the same reference number is applied to the same or similar members. The sections in all cases are as viewed in the direction of the arrows.

Figure 1 is a side elevation of our improved dipper. 100

Figure 2 is a plan view, parts being removed from the upper left-hand portion to show a section along the line 2—2 of Figure 1. 105

Figure 3 is a front elevation, showing the dipper teeth in place.

Figure 4 is a plan view of half of the bolting flange.

Figure 5 is a section of the side of the dipper, taken along the line 5—5 of Figure 1. 110

Figure 6 is a section of the side of the dipper, taken along the line 6—6 of Figure 1.

Figure 7 is a section of the dipper front, taken along the line 7—7 of Figure 3. 115

Figure 8 is a section of the dipper front, taken along the line 8—8 of Figure 3, showing the dipper tooth in position.

Figure 9 is a detail section, taken along the line 9—9 of Figure 4, showing the bolt and shear plug at the joining flanges. 120

Our improved dipper consists of an integrally cast upper, or digging, member 1, and an integrally cast lower, or carrying, member 2, the plane of division 3 being horizontal. 125

The upper casting 1 has integral therewith around the periphery of its open lower end, and projecting outwardly from the sides of the dipper, a bolting-flange 4, whose lower 130

face is finished and abuts the finished upper face of bolting-flange 5, the latter being at the upper periphery of casting 2 and integral therewith.

5 These two bolting flanges 4, 5, are exactly similar in plan, and both lie entirely outside of the volume defined by the inner faces of the dipper. They are both provided with a number of bolt holes 6, 7, drilled to temporary plate, for the reception of bolts 8, 9, with nuts 11.

Of the bolt-holes 6, 7, certain ones, numbered 7, are enlarged throughout a portion of their length for the reception of a shear-plug 10, through which the bolt 9 passes. This construction is shown in detail in Figure 9.

The bail 13 has integral therewith the padlock-sheave-housing 14 for the padlock sheave (not shown); and the ends of the bail are bifurcated for the reception of the bail lug 15 between the bifurcations 16, 17. The bail lug is integral with the upper casting 1, which is reinforced by the flange 12^a, and is hingedly connected with the bail by the bail pin 18.

The upper portion 19 of the side of the upper casting 1 is flared out adjacent the bail lug 15, in order that the inner bifurcation 16 of the bail end shall not project inward beyond the normal inner face of the dipper.

The upper edge of the back of the dipper has integral therewith a flange 20 which serves to stiffen the dipper and, in conjunction with the flange 12, to hold integrally the back-brace lugs 21, which lugs are therefore integral with the casting 1. The back-brace lugs are pin-connected to the back-brace (not shown), through the eye 22. The flange 12 furthermore serves as a protection to bolts 8.

In the upper casting 1, the dipper front consists of an outer wall 23 and an inner wall 24, of which walls the upper portions, at all points except at the spaces occupied by the teeth 25, converge to form a single cutting edge or lip 26. The lip is reinforced by thickening the casting at 27.

The teeth 25 occupy sockets 28, two opposite walls of which are formed by the outer and inner walls 23, 24 of the dipper front. There are no lateral walls to the sockets, the teeth being laterally held in place by the lip-forming joining of the two said walls 23, 24 at their upper part adjacent the lip 26, in conjunction with the upper and lower reinforcing webs 29, 30, respectively. These reinforcing webs, except at the spaces filled by the teeth 25, extend horizontally from the outer wall 23 to the inner wall 24.

At the spaces occupied by the teeth 25 the outer wall 23 is prolonged downward to a continuity with the bolting flange 4; while at the interspaces between the teeth the

outer wall 23 is not continued below the lower reinforcing web 30. Thus there is formed, at each interspace, an aperture 31, to facilitate the insertion or removal of the bolts 8, 9.

At the base of each tooth socket 28, and central to the base of each tooth 25, the bolting flanges 4, 5, have a hole 32 drilled through them. As the teeth are merely frictionally held in the socket, they may easily be removed for repointing or renewal by inserting a short bar in the hole 32 and driving the bar with a hammer. When the tooth wears and becomes shorter, it may be advanced with respect to the socket by inserting in the socket at the base of the tooth a filler or spacer 33, of the same cross section as the tooth.

The lower member 2 has integrally cast therewith handle-connections 34 to which the handle (not shown) is pin-connected, door-hinge lugs 35 to which the door-hinge 36 is pin-connected, a latch-keeper 37, and the bolting flange 5 before described. To these may be added flanges 38 which serve to brace the lugs 34, 35, flanges 39, 40, to brace the bolting flange 5, the latter also stiffening the front and being prolonged downwardly to the bottom band 44 later to be described.

The door hinge 36 carries the door 41, which carries a latch (not shown), and is of the usual construction and need not be more particularly described.

The latch-keeper 37 has the usual latch hole 42 which is provided with a renewable tool-steel bar 43 at the edge which engages the latch.

The bottom of the casting 2 is provided with a bottom band 44 as reinforcement. It is to be noted, especially from Figures 7 and 8, that the bottom band 44 does not project outwardly beyond the plane tangent to the upper part of the dipper front, and therefore opposes no resistance to the digging.

The figures show that there are no bolts or rivets in the body of the dipper, the few bolts used being all in the bolting flanges 4, 5. They also show quite clearly that in the interior of the dipper there are neither projections nor excrescences to obstruct digging or dumping, nor any hollow or pocket to become filled with the excavated material. It may also be seen, especially from Figure 1, that the lower casting 2 flares out, the area of the bottom opening being greater than that of the top. This also aids in attaining ease of dumping.

Having now particularly described and illustrated one form of our improved dipper for excavating machinery, we claim:

1. An excavating dipper, the body portion of which is made up of two cast-metal parts, secured together to form a unitary

- body portion, said parts being joined, the joint cutting the back, the two sides and the front of the dipper, the upper one of said parts being provided with means for the attachment of the hoisting means and with means for the attachment of the handle braces and with means for holding the cutting means, and the lower one of said parts being provided with means for the attachment of the dipper-handle and with means for the attachment of the door hinges; whereby the bending moment due to hoisting takes place in one integral part of said dipper, and the shear due to hoisting is eliminated. 65
2. An excavating dipper, the body portion of which is made up of two cast-metal parts, secured together to form a unitary body portion, said parts being joined, the joint cutting the back, the two sides and the front of the dipper, the upper one of said parts being provided with means for the attachment of the hoisting means and with means for the attachment of supporting means and with means for holding the cutting means, and the lower one of said parts being provided with means for the attachment of the door hinges; whereby the bending moment due to hoisting takes place in one integral part of said dipper, and the shear due to hoisting is eliminated. 70
3. An excavating dipper, the body portion of which is made up of two cast-metal parts, secured together to form a unitary body portion, said parts being joined by means of two outwardly extending flanges secured together. 75
4. A dipper or similar excavating unit, the body portion of which is made up of two cast-metal parts, secured together to form a unitary body portion, said parts being joined by means of two outwardly extending flanges secured together, the joint cutting the back, the two sides and the front of the dipper. 80
5. A dipper or similar excavating unit, the body portion of which is made up of two cast-metal parts, secured together to form a unitary body portion, said parts being joined by means of two outwardly extending flanges secured together, the joint cutting the back, the two sides and the front of the dipper, each of said parts being stiffened by longitudinal and transverse outwardly-extending flanges. 85
6. A dipper or similar excavating unit, the body portion of which is made up of two cast-metal parts, secured together to form a unitary body portion, said parts being joined by means of two outwardly extending flanges secured together by bolts, the joint cutting the back, the two sides and the front of the dipper, each of said parts being stiffened by outwardly-extending flanges. 90
7. A dipper or similar excavating unit, the body portion of which is made up of two cast-metal parts, secured together to form a unitary body portion, said parts being joined by means of two outwardly extending flanges secured together by bolts, the joint cutting the back, the two sides and the front of the dipper, each of said parts being stiffened by outwardly-extending flanges, one of said stiffening flanges being adjacent and parallel to said securing flanges, thus serving to protect said bolts. 95
8. A dipper or similar excavating unit, the body portion of which is made up of two cast-metal parts, secured together to form a unitary body portion, said parts being joined by means of two outwardly extending flanges secured together by downwardly extending bolts, the joint cutting the back, the two sides and the front of the dipper, each of said parts being stiffened by outwardly-extending flanges. 100
9. A dipper or similar excavating unit, the body portion of which is made up of two cast-metal parts, secured together to form a unitary body portion, said parts being joined by means of two outwardly extending flanges secured together, the joint cutting the back, the two sides and the front of the dipper, each of said parts being stiffened by outwardly-extending flanges, all flanges and other projections lying entirely outside the volume defined by the inner faces of the dipper, so that a smooth surface is presented to the excavated material. 105
10. A dipper or similar excavating unit, the body portion of which is made up of two cast-metal parts, secured together to form a unitary body portion, said parts being joined, the joint cutting the back, the two sides and the front of the dipper, the lower one of said parts having its interior flare outwardly downwardly, so as to facilitate the dumping of excavated material. 110
11. A dipper or similar excavating unit, the body portion of which is made up of two cast-metal parts, secured together to form a unitary body portion, said parts being joined, the joint cutting the back, the two sides and the front of the dipper, the upper one of said parts having sockets for the insertion of digging teeth, said teeth being held therein merely by friction. 115
12. A dipper or similar excavating unit, the body portion of which is made up of two cast-metal parts, secured together to form a unitary body portion, said parts being joined by means of two outwardly extending flanges secured together by bolts passing through holes therein, the joint cutting the back, the two sides and the front of the dipper, each of said parts being stiffened by 120

outwardly-extending flanges, said holes being enlarged through part of their lengths, for the insertion of shear-plugs.

13. An excavating dipper, the body portion of which is made up of two cast-metal parts, secured together to form a unitary body portion, said parts being joined by a joint extending transversely of said body

portion, the front face of the lower part being undercut with respect to the upper part, ¹⁰ so that the lower part will take a lesser portion of the wear incident to digging.
